UNITED STATES PATENT OFFICE

HENRY WILLIAM SMITH, OF BIRMINGHAM, ENGLAND

TRAY MOLD FOR USE IN THE MANUFACTURE OF CHOCOLATE BARS AND THE LIKE

Application filed March 14, 1931, Serial No. 522,597, and in Great Britain September 22, 1930.

The present invention has relation to tray molds for use in the manufacture of chocolate bars and the like, of the type comprising a sheet metal or like tray having a plurality of shallow molds arranged side by side, the present invention having for its object to provide for the increased strength of such a device whereby it shall easily withstand the vibration to which it is subjected when passing through the chocolate making mechanism in the operation of separating the bars from the mold.

According to the present invention a plurality of independently constructed sheet metal molds are held in assembled relationship through the medium of longitudinally disposed strips of sheet metal which are connected to the various molds along their edges by means of an interlocking lap joint constituted by a single hook-like flange on the strip which is engaged by corresponding hook-like flanges on each of the molds. The molds may be of a single duplex or triplex character, a series of such molds being united 20 by the interlocking lap joint aforesaid, effected between the molds and the longitudinal strip.

In order that this invention may be clearly understood and readily carried into practice, reference may be had to the appended explanatory sheet of drawings, upon which:—

Figure 1 is a plan view of a tray mold constructed in accordance with the present invention.

Figure 2 is a longitudinal section taken on the line 2—2 of Figure 1.

Figure 3 is a transverse section taken on the line 3—3 of Figure 1.

Figure 4 is an inverted plan view of the mold shown in Figure 1.

Figure 5 is a plan view of a modified mold, and

Figure 6 is a plan view of a further modified mold.

Figure 7 is an inverted plan view of the mold shown in Figure 6.

Figure 8 is an inverted plan view illustrating a still further modification herein-after referred to.

In a convenient embodiment of the present

invention each mold *a* is stamped or pressed up from sheet metal to an oblong formation into a configuration adapted to constitute a bar of chocolate of any well known or desired section. These molds comprise a cavitous portion surrounded by a peripheral flange *a*¹, and it is with respect to the attachment of this peripheral flange to a peripheral tray portion in the same plane that the present invention is particularly directed. The molds *a* may be constructed separately and independently of one another and arranged side by side as shown in the Figures 1, 2 and 3, and be individually attached to the peripheral tray portion *b* which comprises two longitudinal and two end strips of sheet metal suitably united at the corners *b*¹. In this invention the end portions *a*¹ of the molds *a* are attached to the longitudinal peripheral parts *b* constituting the sides of the tray by adjacent edges of these members being turned over to a U or hook formation as at *a*² *b*² (Figure 3) and said formations being interengaged and the seam or union thereby constituted being afterwards advantageously pressed in such a manner that the peripheral tray part lies flush with the top plane of the molds, and the seam or union flattened to either a substantially semi-circular section or a flat oblong section, as may be found most desirable. Such an interlocking seam or lap joint as *a*² *b*² provided between the longitudinal strips *b* and the extremities of the molds not only efficiently secures the whole assembly, but very considerably strengthens the whole device against warping or twisting. The outer peripheral parts *b* which are constituted from the elongated strips of sheet metal may be constructed with downwardly directed double thickness flanges *b*⁴ at their outer edges in well known manner. The corners *b*¹ may be effected by overlapping in combination with soldering. Not only may the extremities *a*¹ of the molds be connected to the peripheral parts *b* of the tray by the aforesaid interlocking lap joint but the end molds *a* may have their side edges *a*³ "lap jointed" to the end strips *b* of the tray and the "lap jointing" operation in any instance may be

assisted by soldering more particularly at the various corners.

In the modification illustrated in Figure 5, the molds are constructed in pairs a a^4 and a double or interlocking seam or lap joint is effected between the ends a^1 of the molds a in the longitudinal strips b . Further, a double or interlocking seam or lap joint a^5 is effected between one duplex mold and the adjacent duplex mold, that is to say, that instead of the molds being placed side by side with abutting edges as in the preceding arrangement, a double or interlocking seam or lap joint is effected between the respective molds.

In the modification illustrated in Figure 6 each of the molds indicated by the reference letter a are constructed independently and are aggregated together with their edges abutting and initially assembled by means of rods c which are located by a soldering operation. In this modification however, as in the preceding arrangements longitudinal strips b are utilized which unite the series of trays a by means of double or interlocking seam or lap joints b^2 .

In the modification shown in Figure 8 a plurality of $\square$ shaped reinforcing rods d are utilized and also a rectangular-shaped rod d^1 .

In any of the modifications rods such as c d d^1 may be utilized for strengthening either the series of molds or the peripheral tray part, or both, the said rods being assembled upon the underside of the tray by a suitable soldering operation, in fact soldering may assist the union of any of the parts when and where desirable.

What I claim as my invention and desire to secure by Letters Patent is:

1. A tray mold comprising a frame, a plurality of marginally flanged molds disposed within said frame, the marginal lateral flanges of the molds being disposed in edge to edge abutting relation, means for securing the end flanges of the molds to the frame, and strips extending in underlying relation to the abutting flanges of the molds and secured to said flanges and to the frame.

2. A tray mold comprising a frame, a plurality of marginally flanged molds disposed within said frame in side to side and end to end relation, means securing the outermost flanges of the outermost molds to the frame, and strips extending in underlying relation to the side and end abutting flanges of the molds and secured to said flanges and to the frame.

In witness whereof I have hereunto set my hand.

HENRY WILLIAM SMITH.
